TRAFFIC CONTROL GATE

John Conrad Stafford, Steubenville, Ohio

Application April 3, 1936, Serial No. 72,623

4 Claims. (Cl. 39—82)

This invention relates to a gate for use in controlling street traffic, such as the passage of motor vehicles and/or pedestrians in different general directions at the intersection of two streets.

More particularly, the present invention contemplates the provision of an improved manually operable gate adapted to be mounted on a corner at the intersection of two streets for controlling traffic along such streets at such intersection, whereby to minimize accidents due to conflicting traffic, etc.

The present invention consists in the novel construction and in the novel combination and arrangement of parts hereinafter more fully described, shown in the accompanying drawings and claimed.

In the drawings:

Figure 1 is a plan view showing a traffic control gate operatively arranged at the intersection of two streets and constructed in accordance with the present invention.

Figure 2 is an elevational view thereof.

Figure 3 is an enlarged fragmentary top plan view thereof.

Figure 4 is an enlarged transverse section on line 4—4 of Figure 2.

Figure 5 is a view similar to Figure 2 illustrating a pole temporarily used as a barrier for the gate when the slight slat-like barrier members of the gate have been accidentally broken off; and

Figure 6 is a section on line 6—6 of Figure 3.

Referring in detail to the drawings, the present invention consists of an upright post or standard 5 adapted to be suitably rigidly mounted in a vertical position at a corner of the intersection of two streets 6 and 7, as illustrated in Figures 1, 2 and 5. The standard or post 5 may be embedded in concrete as at 8, for this purpose, the concrete being placed in a suitable hole 9 formed in the ground as shown more clearly in Figure 2. The post or standard 5 projects a suitable distance above the ground, and fitted and revolubly journaled upon the upper end of this post or standard is a carrier member 10 in the form of a cap or socket formed at the top with a transverse horizontal trough-shaped member 11. The trough-shaped member 11 projects beyond one side of the cap or socket portion of this carrier, and at the other end the sides of said trough-shaped member are provided with extensions in the form of ears 12 between which is pivoted a barrier support consisting of a central tubular socket 13 and spaced parallel socket portions 14 integral with the

socket 13 and disposed in spaced relation at opposite sides of the latter. The recesses of the socket portions 14 are of rectangular cross section as shown in Figure 4 for snug retaining reception of the ends of the respective ones of two slat-like members 15 which cooperate to form a barrier capable of extending entirely across a street when horizontally disposed either in the full line or the dotted line position of Figure 1. The slat-like members 15 may converge into contiguous relation at their outer free ends as shown in Figure 1 where they may be secured together.

The barrier support composed of socket portions 13 and 14 is arranged with its socket portion 13 between the ears 12 of carrier 10, being pivoted to the ears 12 of the latter near one end of said socket portion 13, as at 16. The pivot at 16 is horizontal and provides means whereby the barrier support may be swung relative to the carrier 10 about a horizontal axis in a vertical plane, so that the barrier of the gate may be arranged in the operative horizontal position of Figures 1 and 2 when in use, or in the vertical inoperative position as shown by dotted lines in Figure 2, when not in use.

The trough-shaped member or portion 11 of the carrier 10 is of a size to snugly receive the socket portion 13 of the barrier support when the latter is horizontally disposed as more clearly shown in Figures 4 and 6, thus causing the carrier and the barrier support to turn as a unit without placing a strain upon the pivot 16 when the parts are disposed as in Figures 4 and 6. Such turning movement of the carrier and barrier support is of course about a vertical axis in which the socket portion of the carrier 10 turns on the upper end of the upright or post 5. A suitable bearing may be provided between the post 5 and the carrier 10, particularly a thrust bearing as at 17. Also, suitable means may be provided for securing the carrier on the upper end of the post such as set screws 18 projecting into an annular groove 19 in the upper end portion of post or standard 5.

The socket portions 14 of the barrier support may also have ears 20 which project from corresponding ends of said socket portions 14 and pivotally engage the pivot pin at 16 at the outer sides of ears 12, for greater strength and rigidity. Also, the free ends of the ears 12 of carrier 10 may be extended beyond the ears 20 and rigidly connected by an arch member 21, for added strength.

The movement of the barrier support toward a horizontal position may be suitably adjustably

limited by means of adjusting screws 22 threaded through the projecting end of trough portion or member 11 of the carrier 10 for contact or engagement with the adjacent end of socket portion 13 of the barrier support. Obviously, by adjusting the screws 22, the swinging movement of the barrier support may be properly limited to a position wherein the barrier reaches a truly horizontal position, even though said barrier may sag slightly at its outer end or even though post 5 may yield or bend slightly under the weight of the barrier. This same result can of course be obtained by providing the adjusting screws 22 in the arch-like connection 21 between the ears 12 of carrier 10, in which case the screws will engage the socket portion 13 at the opposite end and at the top of the same.

In order to manipulate the gate, a handle 23 is preferably provided on the end of socket portion 13 opposite that from which the barrier members 15 project, said handle 23 preferably having a shank 24 fitted and secured in the adjacent end of said socket portion 13 as shown clearly in Figure 6.

In operation, the gate is erected on a corner of the intersection of the two streets 6 and 7, preferably as shown in Figure 1, so as to not only control street vehicular traffic but also pedestrian traffic at the intersection. When the barrier is arranged across the street 6 as shown by full lines in Figure 1, traffic may freely flow along street 7. However, when it is desired to stop flow of traffic along the street 7 and permit the flow of traffic along the street 6, the handle 23 is manipulated to revolve the carrier 10 and the barrier support 13, 14 about the axis defined by post 5. This results in horizontal swinging of the barrier from the full line position of Figure 1 to the dotted line position of that figure as indicated by the arrows. While the gate has been shown as mounted so that the barrier will extend across the roadway and side walks of a street in either position of the barrier, it is obvious that a shorter barrier may be used and that the upright or post 5 may be arranged at the curb so that the gate is adapted to merely control vehicular traffic along the respective roadways. Other ways of using the gate, in plurality, for the control of both vehicular and pedestrian traffic, will suggest themselves to those skilled in the art.

Due to reckless driving or the like, the barrier composed of slat members 15 may become broken so as to temporarily render the gate unfit for use. In order to provide for temporarily repairing the gate in this emergency until it can be properly repaired at a time when traffic is not heavy, and in order to permit the continued use of the gate when traffic is heavy, the socket portion 13 is provided as a part of the barrier support. By the provision of the socket portion 13, an ordinary 60 bamboo pole may be readily associated with the barrier support for temporary use, merely by placing one end of the bamboo pole in said socket portion 13 as illustrated clearly in Figure 5 at 25. When use of the gate is not necessary or desired, 65 the barrier may be swung to the dotted line vertical position of Figure 2 by swinging the barrier support relative to the carrier 10 about the pivot 16. The socket portion 13 of the barrier support will engage the cap or socket member of carrier 10 when the barrier is swung to this vertical position, the barrier and its support being slightly overbalanced so as to remain in this position unless manually shifted back to horizontal position. Any suitable means may be provided to 70 lock the barrier in its vertical inoperative position

to prevent unauthorized tampering with the gate when not in use. Obviously, with the barrier vertically disposed it will not interfere with traffic along either street at the intersection, either vehicular or pedestrian traffic.

From the foregoing description, it is believed that the construction and operation as well as the advantages of the present invention will be readily understood and appreciated by those skilled in the art. Minor changes in the details of construction illustrated and described are contemplated within the spirit and scope of the invention as claimed.

What I claim as new is:

1. A gate for controlling traffic at the intersection of two streets or roadways, comprising an upright post, a carrier member journaled on the upper end of said post for rotation about a vertical axis, a barrier support pivoted on said carrier for vertical swinging movement about a horizontal axis and having spaced sockets, an elongated barrier comprising slat-like members having corresponding ends fitted in said sockets of said barrier support, means for limiting the swinging movement of said barrier support to locate the barrier either in a substantially horizontal operative or a substantially vertical inoperative position, and a handle for use in manually rotating the carrier and barrier support about said vertical axis to selectively position said barrier across either desired one of the intersecting streets or roadways.

2. A gate for controlling traffic at the intersection of two streets or roadways, comprising an upright post, a carrier member journaled on the upper end of said post for rotation about a vertical axis, a barrier support pivoted on said carrier for vertical swinging movement about a horizontal axis having spaced side sockets and an intermediate socket, an elongated barrier comprising slat-like members having corresponding ends fitted in said side sockets of said barrier support, means for limiting the swinging movement of said barrier support to locate the barrier either in a substantially horizontal operative or a substantially vertical inoperative position, and a handle fitted in said intermediate socket for use in manually rotating the carrier and barrier support about said vertical axis to selectively position said barrier across either desired one of the intersecting streets or roadways, said carrier comprising a cap formed at the top with a transverse horizontal trough-shaped member, the intermediate socket of said barrier support being arranged to rest in said trough-shaped member when the barrier is disposed in its horizontal operative position.

3. A gate for controlling traffic at the intersection of two streets or roadways, comprising an upright post, a carrier member journaled on the upper end of said post for rotation about a vertical axis, a barrier support pivoted on said carrier for vertical swinging movement about a horizontal axis, an elongated barrier carried by said barrier support, means for limiting the swinging movement of said barrier support to locate the barrier either in a substantially horizontal operative or a substantially vertical inoperative position, and a handle for use in manually rotating the carrier and barrier support about said vertical axis to selectively position said barrier across either desired one of the intersecting streets or roadways, said carrier comprising a cap formed at the top with a transverse horizontal trough-shaped member, said barrier support having a portion adapted to rest in said trough-shaped

member when the barrier is disposed in its horizontal operative position, the means for limiting vertical swinging movement of the barrier support including adjusting screws carried by said carrier and engageable with said barrier support so that the swinging movement of the latter may be adjustably limited.

4. In a gate for controlling traffic at the intersection of two streets or roadways, a barrier sup-

port consisting of a central socket and spaced parallel side sockets integral with and disposed in spaced relation at opposite sides of the central first-named socket, a pair of elongated members fitted at corresponding ends in said parallel socket portions and forming said barrier, and a handle having a shank fitted and secured in one end of said central socket.

JOHN CONRAD STAFFORD.
